UNITED STATES PATENT OFFICE.

JOSEPH C. BELLES, OF LIMA, OHIO.

SANITARY INSERT FOR WASHBASINS.

Application filed February 24, 1928. Serial No. 256,619.

This invention relates to new and useful improvements in sanitary inserts for wash basins, the same being constructed entirely of paper or similar inexpensive material and 5 designed in shape similar to the inner surface of an ordinary wash basin, in which it is to be used as an insert, thereby providing a method whereby a strictly sanitary condition can be maintained through its use as such 10 in hotels, rooming houses, public comfort stations, or other public places; on trains, steamships, or other passenger carrying conveyances, by eliminating the necessity of contact by the user with such part of the bowl 15 as may be infected with disease germs, by supplying an unused, individual means for maintaining water for the purpose of washing or cleansing through its use.

One of the most important objects of this 20 invention resides in the provision of an insert of this character that is so constructed as to enable the insert to closely adhere or conform to the inner surface of a wash basin when disposed therein.

25 Furthermore, the present insert is so constructed as to permit the water to be readily released therefrom prior to any attempt to remove the same from the basin so that the insert can be removed from the basin without difficulty and without having to manipulate 30 the same to prevent the spilling of water over the basin.

With the foregoing and other objects in view as the nature of the invention will be 35 better understood, the same comprises the novel form, combination and arrangement of parts hereinafter more fully described, shown in the accompanying drawings and claimed.

40 In the drawing wherein like reference characters indicate corresponding parts throughout both of the views:

Figure 1 is a longitudinal section of my 45 improved insert as disclosed in a wash basin, the same being illustrated in dotted lines, and

Figure 2 is a transverse sectional view looking toward the rear wall of the insert.

Now having particular reference to the drawing, my insert which is designated by 50 the reference character 5 is constructed of a single sheet of paper or other inexpensive material and of the same general contour as the inner contour of the wash basin dis-

closed by dotted lines in Figure 1 and designated A. The side walls of this insert 5 are 55 formed with vertically extending accordion plaits 6 whereby the said side walls will snugly conform or adhere to the sides of the basin, this adherence being brought about by running the hand around the side walls of the 60 insert, or by the pressure of the water within the insert.

The rear wall of this insert 5 is formed with a vertical score line 7, while formed at the upper edge of the insert at opposite sides 65 of this score line are pull tongues or tabs 8-8. After the basin has been used, the pull tongues or tabs 8-8 are grasped by the thumb and forefinger of the user's hand, and one of the tongues or tabs thence pulled toward the 70 person obviously tearing the back well of the insert upon said score line 7 whereby the water within the insert will be free to flow therefrom into the basin A to facilitate the ready removal of the insert from the basin 75 and this without any liability of drawing a large amount of water from the basin when removing the insert therefrom.

It will thus be seen that I have provided a 80 very simple and useful wash basin insert that is well adapted for all the purposes heretofore designated, and even though I have herein shown and described the invention as consisting of certain detail structural elements it is nevertheless to be understood that 85 some changes may be made therein without affecting the spirit and scope of the appended claim.

Having thus described the invention, what I claim as new and desire to secure by Letters 90 Patent is:—

In an insert for wash basins, a single sheet 95 of ductile material formed to conform with the inner surface of the basin, the side walls of said insert being formed with vertically extending accordion plaits whereby the insert will closely adhere to the interior of the basin, means at the back wall of the insert whereby the same may be readily torn to permit the water to discharge therefrom, said means consisting of a vertical score line, and tabs arranged at the edge of the insert at opposite sides of the score line whereby to facilitate the tearing of the insert upon said score line. 100

In testimony whereof I affix my signature.
JOSEPH C. BELLES.
